UNITED STATES PATENT OFFICE.

ARTHUR J. CAUTIN AND WILFRED DESPINS, OF WATERBURY, CONNECTICUT.

TOP.

1,099,081.

Specification of Letters Patent.

Patented June 2, 1914.

Application filed October 11, 1913. Serial No. 794,699.

To all whom it may concern:

Be it known that we, ARTHUR J. CAUTIN and WILFRED DESPINS, citizens of Great Britain and the United States, respectively, 5 residing at Waterbury, in the county of New Haven and State of Connecticut, have invented certain new and useful Improvements in Tops, of which the following is a specification.

10 This invention has for its object to provide a simple and inexpensive top adapted particularly for children.

The invention consists primarily of a top with peculiar operating means for spinning the same, the body of the top being mounted upon a spindle which is directly actuated by a cross bar slidable thereon and connected with the spindle by an operating cord adapted to be twisted about the spindle and 20 by untwisting to impart a comparatively high rotative speed to the top body. It is contemplated that the body of the top shall have ornamental characteristics, the same being preferably multi-colored so that when 25 rotated it will be very attractive and subserve the amusement purposes of the invention.

In the drawings:—Figure 1 is a perspective view of a top embodying the invention. 30 Fig. 2 is a vertical, longitudinal, sectional view.

Describing the invention specifically, 1 denotes a comparatively long stick or spindle provided with a turning knob or handle 2 at one end and having its other end tapered toward a blunt point as shown at 3. Adjacent to the upper end of the spindle 1 is formed a transverse opening 4 through which passes the operating cord 5 utilized 40 in connection with a cross bar 6 as the means for imparting rotation to the spindle. The bar 6 is tapered toward its ends and centrally thereof is formed with an opening through which the spindle 1 passes, permitting the bar to have a sliding movement longitudinally of the spindle, the cord 5 having its ends passed through openings in the ends of the bar 6 and suitably tied or otherwise secured thereto.

50 On the spindle 1 adjacent to its lower end

is carried the top body 7 which is of the usual somewhat inverted cone shape. The body 7 is detachable from the spindle, being held thereon mainly by friction afforded by the tapering formation of the lower end of 55 the spindle and the proper size of the opening in the body 7 through which the spindle passes. The body 7 is provided with an attractively colored surface having preferably segments of different colors, as readily apparent upon reference to the drawing.

Owing to the provision of the knob 2 at the upper end of the spindle 1 it is necessary to detach the body 7 before the bar 6 can be placed in position on the spindle.

Having thus described the invention, what is claimed as new is:

1. An amusement device comprising a top composed of a spindle provided at one end with a handle and at its other end with a 70 point, a top body mounted on said spindle intermediate its ends, a transverse bar slidable longitudinally of the spindle between said handle and top body, and an operating cord connected at its opposite ends to the 75 ends of said bar and passing intermediate its ends through the spindle.

2. An amusement device comprising a spindle provided at its upper end with an enlargement forming a knob or handle, the 80 other end of the spindle being tapered to a point, a bar arranged transversely of the spindle and having an opening through which said spindle passes, a cord passing through the upper end of the spindle ad- 85 jacent to said knob and having its opposite ends secured to the extremities of said bar, and a top body formed with an opening through which the lower portion of the spindle passes and frictionally engaged with 90 the spindle at such portion to permit of ready detachment.

In testimony whereof we affix our signatures in presence of two witnesses.

ARTHUR J. CAUTIN.
WILFRED DESPINS.
